CLAIM

The ornamental design for a metrology training device, as shown and described.

DESCRIPTION

FIG. 1 is a top, front, right-side perspective view of the metrology training device;

FIG. 2 is a front plan view thereof;

FIG. 3 is a back plan view thereof;

FIG. 4 is a left-side elevational view thereof;

FIG. 5 is a right-side elevational view thereof;

FIG. 6 is a top elevational view thereof; and,

FIG. 7 is a bottom elevational view thereof.

The broken lines depict portions that form no part of the claimed design.
